John Schuman.
Edmund S. Neely,

UNITED STATES PATENT OFFICE.

CHRISTOPHER KNAGGS, OF DETROIT, MICHIGAN.

LOCOMOTIVE-GRATE.

SPECIFICATION forming part of Letters Patent No. 374,839, dated December 13, 1887.

Application filed June 10, 1887. Serial No. 240,904. (No model.) Patented in Canada August 17, 1887, No. 27,460.

To all whom it may concern:

Be it known that I, CHRISTOPHER KNAGGS, of Detroit, in the county of Wayne and State of Michigan, have invented new and useful Improvements in Locomotive-Grates, (for which I have obtained Letters Patent in Canada, dated August 17, 1887, No. 27,460;) and I do hereby declare that the following is a full, clear, and exact description thereof, reference being had to the accompanying drawings, which form a part of this specification.

My invention relates to certain new and useful improvements in fire-boxes and ash-pans for locomotive-engines; and the invention consists in dividing the grate in two parts, with the means for turning the grate-bars of each section independently of the other and in opposite directions, and in the different means for securing the grate-bars in their places; also, in providing means for wetting the ashes in the ash-pan and thawing out the pan in winter, all as more fully hereinafter described and shown.

In the accompanying drawings, which form a part of this specification, Figure 1 is a longitudinal section showing the grates closed. Fig. 2 is a sectional view showing the grates opened. Fig. 3 is a cross-section through the center of the grate-bar. Fig. 4 is a sectional detail showing the pivot of the lower grate. Fig. 5 is an end elevation of the upper grate-bar.

In the drawings like letters indicate like parts.

A is the body of the fire-box, and A' the ash-pan, provided with the flange a, to which the bracket B is attached by the bolt or screw b, the brackets B being in sufficient number to support the bars C C, to which the grate-bars are pivoted. The pivots c c' project from the bars C C, and those on one bar enter a socket, d, in the end of the grate-bar D. The grate-bar D is provided at the opposite end with the arm D', in the outer face of which the groove d' is formed, the upper end of the groove d' being the same distance as the top of the socket d from the upper surface of the grate-bar. The pivot c' enters the groove d', and when it has reached the upper end of said groove the pin 50 d" is inserted through holes in the arm just below the pivot c' to retain the grate-bar in

place. This peculiar construction of the grate-bars in the fire-box enables me to remove any of the grate-bars separately. The grate-bar D is also provided with the curved arm E, to 55 which is attached the bar F. The bar F is attached by the link f to the lever G, by means of which the fireman turns the grate-bars when cleaning the grate. The curved arms E of the forward section of the grate incline inwardly, while the arms of the rear section incline in the opposite direction, so that the grate-bars all turn up toward the center, whereby the coal at the ends has the whole distance between the grate-bars D to clear 60 through instead of the half distance, which would be at one end if they all turned one way. By this construction and arrangement of the grate-bars of the fire-box the fireman in raking his fire can push the live coals on one section 65 and empty the ashes from the other. He can then rake the coals onto the section just cleaned, and then empty the section from which such coals were last taken, thus saving his fire and avoiding the necessity of rebuilding and re-kindling a new one. 70

To the lower inside edge of the ash-pan the bars H H are firmly fastened. At proper intervals holes are drilled through the shell of the ash-pan and the bars H H, through 80 which the pivot-pins K K pass. The grate-bars I I are pivoted on the pins K K. These pivot-pins are provided with a cylindrical head, k, and extend through the bars H H and the shell of the ash-pan, and are secured by a 85 screw-nut on the outer end. The grate-bars I I have a projection, i, on the under side, in which a socket, i', is formed to receive the head of the pivot-pin K, so that any grate-bar may be removed independently of the others. 90

The grate-bars I I are provided on their upper sides with the arm L, to which is pivoted the rod M. This rod M is connected by the link m to the lever N, which is operated by the fireman.

The ash-pan is provided with a pipe, O, which connects by proper pipes with the boiler above and below the water-line to admit either steam or hot water to the pipe O, as desired. The pipe O is laid around three sides of the ash-pan, and is provided with the orifices o, for the purpose of showering the ashes in the pan with 100

water or to admit steam for the purpose of thawing out the ash-pan when frozen in winter.

By the use of the water-pipe I keep the ashes wet, thereby causing them to remain in the ash-pan instead of floating upward and being deposited on other parts of the engine, as is the case with ash-pans as ordinarily constructed. The necessity for using steam to thaw out the ash-pan in winter is too well known to need further explanation.

What I claim as my invention is—
The combination, with the grate-bar I, formed with downwardly-projecting lug i, having socket i', of the bar H and the removable pivot-pin K, provided with cylindrical head k and nut, substantially as described. 15

CHRIS. KNAGGS.
